UNITED STATES PATENT OFFICE.

MAX A. SKALL, OF NEW YORK, N. Y.

DESIGN FOR A DISPLAY-FIXTURE WITH DISPLAY OF HOSIERY.

43,832.

Specification for Design.

Patented Apr. 8, 1913.

Application filed November 22, 1912. Serial No. 733,005. Term of patent 7 years.

To all whom it may concern:

Be it known that I, MAX A. SKALL, a citizen of the United States, residing at New York city, in the county and State of New York, have invented a new, original, and ornamental Design for a Display-Fixture with Display of Hosiery, of which the following is a specification, reference being had to the accompanying drawing, forming part thereof.

The figure is a front, perspective view of my new design.

I claim:

The ornamental design for a display fixture with display of hosiery, as shown.

MAX A. SKALL.
